(57) **CLAIM**

The ornamental design for a seat post clamp assembly, as shown and described.

DESCRIPTION

FIG. 1 is a rear, left, and top perspective view of a seat post clamp assembly embodying the new design;
FIG. 2 a front, right, and bottom perspective view thereof;
FIG. 3 is a top plan view thereof;
FIG. 4 is a bottom plan view thereof;
FIG. 5 is a left side elevational view thereof;
FIG. 6 is a right side elevational view thereof;
FIG. 7 is a rear elevational view thereof;
FIG. 8 is a front elevational view thereof;
FIG. 9 is a rear, left, and top perspective view thereof for an embodiment of FIGS. 1-8, with certain portions set forth in dashed or dot-dash lines; and,
FIG. 10 is a bottom plan view thereof.

The dash lines, the areas within them, and the areas bounded by dot-dash lines that are within portions of the seat post clamp assembly defined by solid lines depict portions of the seat post clamp assembly that form no part of the claimed design. The broken lines immediately adjacent the shaded areas represent the bounds of the claimed design while all other broken lines are directed to environment and are for illustrative purposes only; the broken lines form no part of the claimed design.
